UNITED STATES PATENT OFFICE.

LEONARD HENKLE, OF ROCHESTER, NEW YORK.

DESIGN FOR A LAMP-BURNER.

SPECIFICATION forming part of Design No. 17,090, dated February 8, 1887.

Application filed July 30, 1886. Serial No. 209,587. Term of patent 7 years.

To all whom it may concern:

Be it known that I, LEONARD HENKLE, a citizen of the United States, residing at Rochester, in the county of Monroe and State of New York, have invented and produced a new and original Design for Lamp-Burners, of which the following is a specification, reference being had to the accompanying drawing, forming part thereof.

10 The drawing shows a perspective view of my design for lamp-burners.

A represents the reservoir of a lamp, having a flat annular portion, A', for its upper terminus. Within this annular portion is fitted the 15 lamp-burner B, having an annular ledge, C, which protrudes slightly, as shown, and seats upon the annular rim A' of the lamp-reservoir. Above the ledge C, and forming the middle part of the burner, is a vertical perforated band, D. Over this is a bead, C', pro-

jecting, as shown, and surmounting this, and forming the top part of the burner, is the lamp-chimney holder E. This chimney-holder has a vertical band, E', which protrudes beyond the line of vertical perforated band D.

The leading feature of my design consists of the vertical perforated band D, with the annular ledge C below and the protruding chimney-holder above.

I claim as new and of my invention—

The design for a lamp-burner herein shown and described, which consists in a vertical perforated band, D, the annular ledge C beneath the band, and the holder E, having a vertical band, E', protruding beyond the perforated band.

LEONARD HENKLE.
